HEAD MOTION FOR LOOMS.

Application filed September 10, 1927. Serial No. 218,759.

This invention relates to a head motion for looms and particularly to certain improvements in a head motion of the type in which vibrator gears are mounted for selective engagement with either one of two segmental cylinder gears, this type of head motion being commercially known as a "Knowles head." The application is a continuation in part of our prior application, Serial No. 70,123, filed by us on November 19, 1925.

In the operation of a loom, it is frequently desirable or necessary to turn the loom backward, especially in order to permit a pick-out of weft threads after a defect in weaving has occurred. It is also desirable, particularly in heavy looms, that the mechanism be so constructed that the loom may be turned backward by power. This operation has not previously been possible in looms equipped with the Knowles head, as the gear centers in the Knowles head were placed too far out of alignment to permit proper tooth clearance when the vibrator gears were reversed. A head motion of the usual form is shown in patent to Hutchins, No. 454,135, issued June 16, 1891.

If the direction of rotation of the cylinder gears be reversed in a Knowles head, such as is shown in said patent, the teeth of the vibrator gears would lock with the teeth of the cylinder gears instead of meshing therewith, and the device would thus become inoperative.

It is the object of our invention to provide a construction in a Knowles head which may be driven in either direction and which will be operable when driven either forward or backward. To this end, we preferably arrange the gear centers more nearly in direct or in approximate alignment than usual, and we also allow increased clearance between the gears. We further provide an intermediate neutral position for the vibrator gears, in which position they are out of engagement with both of the cylinder gears. We also provide a special pattern chain effective to move the vibrator gears to upper, lower, or intermediate positions as desired.

A further object of our invention is to provide means for stopping each vibrator gear in certain definite angular positions, by which

subsequent operative engagement of said vibrator gear by the alternate cylinder gear will be insured and as a result of which extreme accuracy in timing will be rendered less essential.

Our invention further relates to arrangements and combinations of parts which will be hereinafter described and more particularly pointed out in the appended claims.

A preferred form of the invention is shown in the drawings in which

Fig. 1 is a front elevation of a loom embodying our improvements;

Fig. 2 is an enlarged front elevation of the head motion, with the front portion of the head motion frame removed;

Figs. 3 to 6 are diagrammatic views, showing different successive positions of the vibrator gears and cylinders;

Fig. 7 is a view of certain parts, similar to Fig. 2, but in a different operative position;

Fig. 8 is a detail plan view, looking in the direction of the arrow 8 in Fig. 2;

Fig. 9 is an enlarged front elevation of a portion of the pattern chain;

Fig. 10 is a plan view of the parts shown in Fig. 9.

Referring to the drawings, we have shown a loom having a frame 10, harnesses 11 and a driving shaft 12 connected by gears 13, 14, 15 and 16 to an electric motor 17 controlled by a reversing switch 18. The switch 18 is provided with an arm 19 connected by a link 20 and bell crank 21 to a rod 22 by which the operation of the loom may be conveniently controlled or reversed. The harnesses 11 are connected to the usual harness jacks 25, which in turn are connected by links 26 to the vibrator gears 27.

The gears 27 are mounted on vibrator levers 28 and are positioned between upper and lower segmental actuator cylinder gears 30 and 31. These gears 30 and 31 are continuously rotated from the driving shaft 12 through gears 32 and 33, bevel gears 34 and 35, and an upright shaft 36 suitably connected by gears not shown to the cylinder gears 30 and 31.

All of the parts thus far described are substantially of the usual construction except that the centers of the vibrator gears 27 and

cylinder gears 30 and 31 are not the same as usual and that increased clearance is provided between the vibrator gears and the cylinder gears. This clearance is sufficient to permit the vibrator gears to occupy an intermediate neutral position in which these gears are out of the path of engagement with either the upper or the lower cylinder gears. ⁵ Vibrator gears 27 are somewhat different from those ordinarily employed as regards the lengths of the blank spaces.

The vibrator levers 28 are shown as provided with gear teeth 40 engaged by corresponding teeth 41 on the ends of pattern levers 42 each having a roll 43 thereon for engagement by the links of a pattern chain 44. It will be understood that a separate lever 42 and a separate series of links on the pattern chain are provided for each vibrator lever 28. While we have shown a lever 42 for each vibrator, yet we do not wish to be limited to this construction as other means may be provided to raise said vibrator levers.

The extreme upper and outer ends of vibrator levers 28 are provided with additional teeth 45 which are positioned for engagement by a latch or bar 46 mounted on a bell crank 47 and actuated by a cam 48 rotatable with the lower cylinder gear 31.

³⁶ The pattern chain 44 (Figs. 9 and 10) is preferably formed of a series of links 50, 51 and 52 corresponding to the upper, lower and intermediate positions of the vibrator gears 27. Additional connecting links 53, 54, and 55 are provided for guiding the rolls 43 from one to another of the links 50, 51 or 52.

⁴⁰ In the usual Knowles head, the vibrator lever can assume two positions only, that is, it must be either up or down. The gear mounted on each lever is provided with diametrically opposite blank spaces one of which is longer than the other to permit the vibrator gear to remain adjacent a cylinder gear without meshing therewith. This wide blank space makes it impossible to get enough teeth on the gear to enable the latter to be driven positively a complete half turn in both directions.

⁴⁵ We are able to make our vibrator gear with equal narrow blanks, because of the intermediate position and we thus get enough teeth to turn the gear positively through more than 180° in either direction. This construction of the gears is shown in Figs. 2 to 7 inclusive.

⁵⁰ An important feature of our invention lies in the proportioning of the slot 27^a in each vibrator gear 27, so that the gear will be stopped by the vibrator lever stud 28^a in the position shown in Fig. 3 or in the position shown in Fig. 6, according to the direction of rotation. In each case, the contact face of the tooth to be next engaged lies in the path of the leading tooth on the actuator cylinder gears. The effective length of slot 27^a is substantially equal to 180° plus the arcuate

length of one of the blank spaces 27^b of the vibrator gear.

Obviously, a vibrator gear cannot be given two successive movements in the same direction and the pattern chain must be made up to provide alternate operations only. A reversal of the gears, however, will also reverse the pattern chain and the alternate sequence of operations will be maintained.

⁷⁵ Successive positions of the cylinders and vibrator gears are shown in Figs. 3 to 6 inclusive. In Fig. 3, the vibrator gear 27 is about to be engaged and rotated by the lower cylinder gear 31. In Fig. 4, the rotation of the gear thereby is just ended. In Fig. 5, the ⁸⁰ vibrator gear 27 has been moved to intermediate or neutral position and in Fig. 6 the gear 27 has been raised and is about to be engaged by the upper cylinder gear 30. Fig. 2 ⁸⁵ shows the neutral position preceding the operative relation of Fig. 3 and Fig. 7 shows additional parts but otherwise corresponds to Fig. 5.

To accomplish the proper movement of the ⁹⁰ vibrator gear we make the pattern chain connecting links 53, 54, and 55 with cam surfaces so designed that they will raise the vibrator gear to permit the advancing actuating or cylinder teeth to engage the gear teeth and turn the gear an angle in excess of 180° .

⁹⁵ Reference to Fig. 9 will show that the cam surfaces of the links 53, 54 and 55 are concave so that the lifting movement caused thereby will be relatively slow at the start and relatively rapid at the end of the movement.

¹⁰⁰ Another feature of our invention relates to the pivotal point for the vibrator lever 28 and the connection between the connectors 26 and the harness jacks 25. By referring to Fig. 2 it will be seen that gudgeon 56 is located on an extension of the jack and is below the pin 57 on which the vibrators are mounted. By referring to Fig. 7 where the parts are shown in the opposite position, it will be seen that the gudgeon 56 has been moved to a position ¹⁰⁵ above the pin 57. This action is due to the fact that the gudgeon 56 is always to the left of a vertical line passing through the axis of the jacks 25. It will be seen that the pivotal connection 58 between the connector and gear ¹¹⁰ is below a line joining the axis of the gears and the pin 57 in all positions of the vibrator gear 27. The effectiveness of the locking of the connector depends upon the distance the connection 58 lies below a line joining the ¹¹⁵ gudgeon 56 and the axis of the gear 27.

¹²⁰ When the parts change from the position shown in Fig. 2 to that shown in Fig. 7 this distance would be too small unless gudgeon 56 were raised as the connection 58 passes to the other side of the axis of the vibrator gear 27. By having gudgeon 56 always on the same side of a vertical line passing through the axis of the jacks 25, it will be seen that the gudgeon 56 rises so that when pivot 58 is in ¹²⁵ 130

the position shown in Fig. 7 it will still be below a line joining the gudgeon 56 and vibrator gear center.

An important feature of the invention relates to the location of the vibrator gear centers with respect to the centers of the actuating cylinders. As previously stated the usual Knowles head is constructed with the vibrator gear offset considerably from a line joining the centers of the actuator cylinder gears. If the vibrator gears shown herein were mounted on slides moving in guides parallel to a line joining the centers of the actuator cylinders 30 and 31 the centers could advantageously be so located that the pivot of the vibrator gears and the centers of the cylinders 30 and 31 would all be in a plane. The vibrator gears, however, are mounted on levers which move pivotally about a center comparatively close to the actuator cylinder gears, and because of this fact the desired clearances between the cylinder gears and the vibrator gears are not obtained when the centers are in alignment. It is for the purpose of securing proper clearances that the vibrator gear center is placed to that side of the line joining the centers of the cylinder gears which is opposite the pivotal center of the vibrator gear.

Having thus described the preferred construction of our improved head motion, the operation thereof will be easily apparent. When a pattern lever roll 43 rests upon one of the low links 51, the corresponding vibrator gear 27 will be engaged and rotated by the lower cylinder gear 31. If a roll 43 is supported by one of the high links 50, the corresponding gear 27 will be engaged and rotated by the upper cylinder gear 30.

After each operative movement by either the upper or the lower cylinder gear, the vibrator gear is moved immediately to intermediate or neutral position, before the driving teeth of the cylinder gear can again engage the vibrator. It is not necessary that the vibrator remain in intermediate position, as it can move from high to low position, as suggested at the left hand end of Fig. 9.

If it is desired to leave a harness jack in the same position for two picks, the pattern chain is designed to support the corresponding roll 43 on one of the intermediate links 52, which will hold the corresponding vibrator gear 27 out of engagement with either the upper or lower cylinder gears and will thus retain the corresponding harness jack in unchanged position. Successive links 52 may be used to prolong the dwell of the jack until the pattern chain raises or lowers the roll 43.

By thus moving the vibrator gears from inoperative to operative position in timed relation to the rotation of the cylinder gears, and by stopping the vibrator gears in the positions shown and described, we are able to

cause the cylinder gears to engage easily and to mesh correctly with the vibrator gears when the cylinder gears are rotated in either direction.

The use of the additional pattern levers 42 provides increased motion of the vibrator gears for a given variation in the height of the chain links, but it will be understood that the use of these additional levers is optional and that other suitable and well known arrangements of the connections between the pattern chain and the vibrator levers may be used when desired. While the head motion has been described in connection with harness jacks, it is also of utility in the operation of drop box mechanism.

Reference to Figs. 1 and 2 will show that the pattern chain drive is different from that ordinarily employed on motions of this type. The chain 44 is built up of the small flat links shown in Figs. 9 and 10 and is trained over a sprocket cylinder 70 somewhat larger than the usual chain cylinder and having twice the usual number of sprocket teeth. The cylinder 70 receives the same angular movement as the usual corresponding part in the Knowles head, that is, it moves one-sixth of a turn for each pick of the loom, but during this fractional movement two successive links are moved under the roll 43. The first of the pair of links corresponding to each pick effects vertical movement of the roll 43 and the second link provides for the dwell. To give this motion upright shaft 36 has a miter gear 71 meshing with a second miter 72 which is fast on lower cylinder gear shaft 73. Said shaft 73 also carries pinion 74 which meshes with spur gear 75 fast with sprocket 70. The ratios are such that for each revolution of shaft 36 gear 75 makes a sixth of a turn and two teeth of cylinder sprocket 70 pass under roll 43. We do not wish to be held to the stated ratio between shaft 36 and gear 75, but it is desirable to have the sprocket 70 present two chain links under the roll 43 for each pick of the loom.

From the foregoing it will be seen that we have provided a reversible head wherein the vibrator gear has equal and diametrically opposite blank spaces so disposed when the vibrator gear is normally at rest that a line joining the centers of the blank spaces will be oblique with respect to a line passing through the centers of the cylinder gears and it will furthermore be seen that when the vibrator gear is in one normal position the inclination of these lines will be in one direction and when the vibrator gear is in the other of its normal positions the inclination will be in the opposite direction. The inclination may be equal for both positions but we do not wish to be held to this limitation as we find in practice that a head will operate satisfactorily and be reversible if the centers of the vibrator gear and the cylinder gears are such that the

two inclinations referred to are not identical. Also, it will be seen that the effective length of slot 27^a is substantially equal in degrees of arc to 180° plus the arcuate length of one of the blank spaces 27^b on the vibrator gear. In this way we provide means not only for moving the vibrator gear positively through an angle in excess of 180° so as to provide a desirable lock to prevent accidental displacement of the harness levers, but we also leave the blank spaces on the vibrator gears in proper position for the next cooperation of one or the other of the cylinder gears. By the use of the head shown herein it is unnecessary to have the reversing key shown in the patent to Hutchins #490,890. Furthermore, the centers of the vibrator and actuator gears, while preferably not in exact alignment, are more nearly so than is the case with the usual 20 Knowles head.

While we have described our invention as applied to the control of harness movements, it will be evident that the invention may be utilized in exactly the same way in the control of drop box movements where vibrator gears and levers are used and such use is within the scope of our invention.

Having thus described our invention and the advantages thereof, we do not wish to be limited to the details herein disclosed, otherwise than as set forth in the claims, but what we do claim is:

1. In a reversible head motion for looms, in combination, a plurality of vibrator gears, upper and lower driving cylinder gears, the axes of all of said gears being closely adjacent a single plane, and means to move a selected vibrator gear from one cylinder toward the other with a motion which is relatively slow at the start and relative rapid at the end, whereby less power is required to start the movement of said vibrator gear.

2. In a reversible head motion for looms, in combination, a plurality of vibrator gears, continuously moving upper and lower driving cylinder gears, vibrator levers, and pattern surface means effective to hold said vibrator levers and gears in upper or lower driving position or in intermediate neutral position, said gears being effectively engageable when rotating in either direction.

3. In a reversible head motion for looms, in combination, a plurality of vibrator gears, continuously moving upper and lower driving cylinder gears, vibrator levers, means to move said vibrator levers and gears to upper or lower driving position or to intermediate neutral position, said gears being effectively engageable when rotating in either direction, and means to lock said vibrator levers and gears either in upper, lower or intermediate neutral position.

4. In a reversible head motion for looms, in combination, a plurality of vibrator gears, upper and lower driving cylinder gears, vi-

brator levers, and means to move said vibrator levers and gears to upper or lower driving position or to intermediate neutral position, said gears being effectively engageable when rotating in either direction, and said lever moving means including a pattern chain having high, low and intermediate links.

5. A reversible head motion for looms comprising vibrator gears, and upper and lower driving cylinder gears, the axes of all of said gears being located substantially in a single plane, and means to drive said cylinder gears in forward and rearward directions.

6. A reversible head motion for looms comprising vibrator gears and upper and lower driving gears, the axes of all of said gears being located substantially in a single plane, a motor to drive said cylinder gears in forward and rearward directions, and a reversing switch controlling said motor.

7. A reversible head motion for looms comprising vibrator gears, upper and lower driving cylinder gears, vibrator levers, means to hold said vibrator levers and gears in upper or lower driving position or in intermediate neutral position, means to drive said cylinder gears in forward and rearward directions, and means to selectively engage said vibrator gears with said cylinder gears when the latter are rotating in either forward or rearward direction.

8. A reversible head motion for looms comprising vibrator gears, upper and lower driving cylinder gears, vibrator levers, and means to hold said vibrator levers and gears in upper or lower driving position or in intermediate neutral position, said gears being effectively engageable when rotating in either direction, said cylinder gears being spaced apart to provide an intermediate neutral position for said vibrator gears in which position the paths of the outer ends of the teeth of said vibrator gears and said cylinder gears do not contact at any point.

9. A reversible head motion for looms comprising vibrator gears, continuously moving upper and lower driving cylinder gears, vibrator levers, and means to move said vibrator levers and gears to selectively engage said cylinder gears, said cylinder gears and vibrator gears being equally operable and effective when said cylinder gears are rotated in either direction.

10. A reversible head motion for looms comprising vibrator gears, continuously moving upper and lower driving cylinder gears, vibrator levers and means to move said vibrator levers and gears to upper and lower driving positions and to intermediate neutral position, each vibrator gear having a blank space representing a single tooth only at two diametrically opposite points on its periphery.

11. A reversible head motion for looms comprising vibrator gears, continuously moving upper and lower driving cylinder gears, vibrator levers, means to move said 5 vibrator levers and gears to upper and lower driving positions and to intermediate neutral position, and means to stop each vibrator gear with the contact face of the leading tooth to be next engaged by a cylinder gear positioned substantially on the line joining the centers of said vibrator gear and said cylinder.

12. A reversible head motion for looms comprising vibrator gears, continuously 15 moving upper and lower driving cylinder gears, vibrator levers and means to move said vibrator levers and gears to upper and lower driving positions and to intermediate neutral position, each vibrator lever having 20 a stop and each vibrator gear having a segmental slot for said stop and of such length that said gear when rotated in either direction will be stopped with the contact face of the leading tooth to be next engaged by a cylinder gear positioned substantially on the line 25 joining the centers of said vibrator gear and said cylinder.

13. A reversible head motion for looms comprising vibrator gears, continuously 30 moving upper and lower driving cylinder gears, vibrator levers, means to move said vibrator levers and gears to upper and lower driving positions and to intermediate neutral position, and means to stop each vibrator 35 gear with the contact face of the leading tooth to be next engaged by a cylinder gear positioned substantially on the line joining the centers of said vibrator gear and said cylinder, and having the corresponding leading 40 tooth on the opposite side of the gear diametrically spaced from said first-mentioned tooth.

14. In a reversible head motion for looms, a pair of oppositely rotating segmental actuator cylinder gears, a vibrator lever, a vibrator gear rotatably mounted on the latter and having an arcuate slot, a stop fixed with respect to the lever and extending into the slot, said vibrator gear having two diametrically opposite blank spaces of equal length, the effective length of the arcuate slot in the vibrator gear being equal to 180° plus the arcuate length of one of the blank spaces of the vibrator gear, each end of the arcuate 55 slot engaging the stop on the vibrator lever to limit movement of the vibrator gear, and harness mechanism operatively related to the vibrator gear.

15. In a reversible head motion for looms, 60 a pair of oppositely rotating segmental cylinder gears, a vibrator lever, a vibrator gear rotatably mounted on the lever and having an arcuate slot formed therein, a stop secured to the vibrator lever and extending into the slot of the vibrator gear to engage both ends

of said arcuate slot, said vibrator gear being formed with two sets of teeth which are separated by equal and diametrically opposite blank spaces, the effective length of the slot in the vibrator gear being equal substantially 70 to the arcuate distance from one end tooth of one of the group of teeth to the other end tooth of the same group of teeth measured across both blank spaces.

16. In a reversible head motion for looms, 75 a pair of oppositely continuously rotating actuator segmental cylinder gears, a vibrator lever, a vibrator gear rotatably mounted on the vibrator lever and located between the cylinder gears, said vibrator gears having 80 diametrically opposite blank spaces of equal length, said vibrator gear assuming two normal different angular positions with respect to a line joining the centers of the cylinder gears, a line passing through the centers of 85 the blank spaces on the vibrator gear being oblique with respect to the line joining the centers of the cylinder gears when said vibrator gear is in either of its two normal positions, and harness connections operatively related to the vibrator gear.

17. In a reversible head motion for looms, 90 a pair of oppositely continuously rotating actuator segmental cylinder gears, a vibrator lever, a vibrator gear rotatably mounted 95 on the vibrator lever and located between the cylinder gears, said vibrator gears having diametrically opposite blank spaces of equal length, said vibrator gear assuming two normal different angular positions with 100 respect to a line joining the centers of the cylinder gears, a line passing through the centers of the blank spaces on the vibrator gear being oblique with respect to the line joining the centers of the cylinder gears when 105 said vibrator gear is in either of its two normal positions, the line passing through the centers of the blank spaces being oblique in one direction with respect to the centers of the cylinder gears when the vibrator gear is in one of the normal positions, and oblique in the opposite direction with respect to the center of the cylinder gears when the vibrator gear is in its other normal position of equal obliquity, and harness connections 110 operatively related to the vibrator gear.

18. In a reversible head motion for looms, 115 a pair of oppositely continuously rotating mutilated actuator cylinder gears, a vibrator lever, a vibrator gear rotatably mounted on 120 said lever and located between the actuator gears, means to give said vibrator lever and gear three positions with respect to the actuator gears, one wherein the vibrator gear will mesh with the lower actuator gear, and 125 another wherein said vibrator gear will be out of mesh with both of said actuator gears, the vibrator gears having two diametrically opposite blank spaces of equal extent, one blank space lying to one side of a vertical 130

line passing through the axis of a vibrator gear and the other blank space lying to the other side of such a vertical line passing through the axis of the vibrator gear when the vibrator gear is in normal position, said vibrator gear being pivoted to the vibrator lever at a point slightly beyond an imaginary line passing through the centers of the actuator gears and said pivot for the vibrator gear being so located that the imaginary line passes between said pivot and the center about which the vibrator gear moves.

19. In a reversible head motion for looms, a pair of oppositely continuously rotating actuator segmental cylinder gears, a vibrator lever, a vibrator gear rotatably mounted on

the vibrator lever and located between the cylinder gears, said vibrator gear having diametrically opposite blank tooth spaces of equal length, means to stop said vibrator gear in either one of two normal positions of rest, in each of which positions a line passing through the centers of the blank tooth spaces will be oblique to a line joining the centers of the cylinder gears, pattern controlled means effective to shift said vibrator gear, and harness mechanism controlled by the vibrating gear.

In testimony whereof we have hereunto affixed our signatures.

CHESTER L. HUSSEY.

WILLIAM H. STEBBINS.
